Attorney

UNITED STATES PATENT OFFICE.

JOHN L. TAYLOR, OF BOZEMAN, MONTANA.

NON-REFILLABLE BOTTLE.

SPECIFICATION forming part of Letters Patent No. 650,282, dated May 22, 1900.

Application filed December 29, 1899. Serial No. 741,984. (No model.)

To all whom it may concern:

Be it known that I, JOHN L. TAYLOR, a citizen of the United States, residing at Bozeman, in the county of Gallatin and State of Montana, have invented certain new and useful Improvements in Non-Refillable Bottles; and I do declare the following to be a full, clear, and exact description of the invention, such as will enable others skilled in the art

10 to which it appertains to make and use the same, reference being had to the accompanying drawings, and to the letters of reference marked thereon, which form a part of this specification.

15 This invention relates to new and useful improvements in non-refillable bottles; and it consists in the provision of a stopper which is preferably made up of two sections carrying a suitable valve, said stopper adapted when 20 adjusted in place within the neck of a bottle to be securely locked therein, thus making it impossible to remove the same without destroying the neck of the bottle.

More specifically the invention resides in 25 the provision of a stopper-locking device for bottles in which the neck of the bottle is internally threaded and provided with pockets in its inner walls which are provided to hold balls which pass through an aperture in the 30 threaded cork or stopper as the latter is being screwed into place within the neck and after the stopper has been screwed down the balls which are held in said pockets adapted to roll out of said pockets and into pockets in 35 the circumference of the stopper, in which they are permanently held and from which they are prevented from escaping by means of the peculiar shape of the pocket, a portion of each ball extending outside of the stopper 40 and coming in contact with the inner wall of the neck, thus making it impossible to turn the stopper in either direction and necessitating the breaking of the neck of the bottle if it is desired to remove the stopper.

45 To these ends and to such others as the invention may pertain the same consists, further, in the novel construction, combination, and adaptation of parts, as will be hereinafter more fully described and then specifically 50 defined in the appended claims.

My invention is clearly illustrated in the accompanying drawings, which, with the let-

ters of reference marked thereon, form part of this application, and in which drawings similar letters of reference indicate like parts throughout both views, in which—

Figure 1 is a central vertical section through a bottle having a stopper embodying my invention. Fig. 2 is a detailed view of the stopper and sectional views of the neck of the bottle.

Reference now being had to the details of the drawings by letter, A designates the neck of the bottle, which has an internal thread B, and at its lower end is an apertured disk, the aperture in which leads into the interior of the bottle. In the walls of the neck at locations one above the other, but preferably on opposite sides of the neck, are the pockets C and D, which are adapted to receive the balls E while the stopper F is being screwed down into its proper position. The stopper F is made up of two sections and is threaded about its circumference, so as to screw into the threads of the neck. The lower end F' of the stopper has threaded connection with the upper part, and the adjacent ends of the sections of the stopper are hollowed out and tapered to receive a valve H. This valve H is held seated by means of the ball K, as shown in the drawings, and leading from the upper end of said stopper centrally is an aperture or duct which opens through the circumference of the stopper at the point L and then turns at an angle and communicates with the hollowed-out or tapered portion in which said valve is seated. Through this irregular-shaped duct the liquid from the bottle is adapted to pass in emptying the bottle. When the bottle is inverted, the valve will be opened to allow the liquid to pass by the same; but when the bottle is right side up the valve is held seated by means of the ball-bearing described.

In order to lock the stopper within the neck of the bottle, the two balls E and E' are employed. One of said balls is inserted in the aperture or duct in the upper end of the stopper after the same is partially screwed into the neck a sufficient distance, so that the outlet of said duct will come opposite the upper pocket D in the inner wall of the neck. When in this position, the ball will roll out of the duct and into said pocket. In placing

the second ball in its locking position the stopper is screwed down until the opening of the duct through the circumference of the stopper comes opposite the second or lower 5 pocket in the inner circumference of the neck, and said ball will roll out of the stopper and into the pocket, and as the stopper is screwed down farther a sufficient distance, so that the pockets Q having outwardly and upwardly 10 extending walls come opposite said pockets, said balls, which have been previously held in the pockets of the neck, will roll down the inclined surface of the pockets in the neck and into the pockets Q. These pockets Q are 15 slightly shallower than the diameter of the balls, so that the latter will extend out a short distance beyond the circumference of the stopper. When the balls have left the 20 pockets of the neck and rolled into the pockets in the stopper F and it is attempted to unscrew the stopper, the projecting portions of the locking-balls will come in contact with the inner threaded wall of the neck, and it 25 will be impossible to remove the stopper without first breaking the neck. As the bottle cannot be refilled without first removing the cork or stopper, the bottle is rendered useless for a second filling. When the stopper is in place, its lower end comes adjacent to or 30 against the apertured disk at the base of the neck and the aperture in the lower end of said stopper registers with the aperture in the disk portion of the neck.

From the foregoing it will be observed that 35 as the bottle is held in its normal position the valve is held seated, but as the bottle is inverted the ball falls by gravity into the V-shaped end of the valve-chamber and the valve, falling back, will allow the liquid to 40 pass by one side of the valve and through the duct in the stopper.

Having thus described my invention, what I claim to be new, and desire to secure by Letters Patent, is—

1. A non-refillable bottle, having an internally-threaded neck, a stopper with duct through same, and having a threaded circumference, balls adapted to be seated in pockets in the inner wall of the neck, while the stopper is being screwed in place, said balls designed to roll into retaining-pockets in the circumference of the stopper, and prevent the latter from unscrewing, as set forth. 45

2. A non-refillable bottle, comprising an internally-threaded neck having an integral apertured disk at its lower end, a stopper with valve therein, a duct leading through said stopper, pockets with flaring walls in the inner wall of the threaded neck designed to temporarily hold locking-balls, the stopper having retaining-pockets into which said balls are designed to roll when the pockets come together on opposite sides, as described and for the purpose set forth. 55

3. In combination with a bottle having internally-threaded neck, the locking-balls, the sectional and threaded stopper, pockets in the inner circumference of the neck and outer circumference of said neck, the lower section of the stopper having threaded connection with the upper section, the adjacent ends of the stopper-sections being recessed out to form a valve-chamber, a valve seated therein and a ball resting on said valve and duct, as described. 65

In testimony whereof I affix my signature in presence of two witnesses.

JOHN L. TAYLOR.
